[57] CLAIM

The ornamental design for a fishing reel body, as shown
and described.

DESCRIPTION

FIG. 1 is a front and right side perspective view of a
fishing reel body, showing my new design;

FIG. 2 is a rear, top and left side perspective view
thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a rear elevational view thereof.

*Fig. 1**Fig. 2**Fig. 3**Fig. 4**Fig. 5**Fig. 6**Fig. 7**Fig. 8*
